UNITED STATES PATENT OFFICE.

ROBERT B. SWART, OF DETROIT, MICHIGAN, ASSIGNOR TO THE HIGGIN MANUFACTURING COMPANY, OF NEWPORT, KENTUCKY, A CORPORATION OF WEST VIRGINIA.

WINDOW-SCREEN.

1,100,668.

Specification of Letters Patent. Patented June 16, 1914.

Application filed December 14, 1912. Serial No. 736,721.

To all whom it may concern:

Be it known that I, ROBERT B. SWART, citizen of the United States, residing at Detroit, county of Wayne, State of Michigan, have invented a certain new and useful Improvement in Window-Screens, and declare the following to be a full, clear, and exact description of the same, such as will enable others skilled in the art to which it pertains to make and use the same, reference being had to the accompanying drawings, which form a part of this specification.

This invention relates to window screens, especially adapted for ventilators or revolving sashes.

It has for its object a screen adapted for this kind of windows which is practically insect proof and which does not take up the room and have the ungainly appearance of the box screen heretofore in use.

Figure 1, is a sectional perspective of the sash, frame and screens. Fig. 2, is a vertical section of the same. Fig. 3, is a section of the frame bar and guide taken on the line 3—3 of Fig. 1. Fig. 4, is a partial section of the contact strip and the side sash bar, taken on the line 4—4 of Fig. 1. Fig. 5, is a detail in perspective of the lower screen and its yielding support.

Fig. A, is the swinging sash or ventilator, provided with the usual sash bars 1 which hold the glass and which have lip flanges 1^a adapted to fit over a projecting flange 2 in the frame B; the opposite side of the sash bar 1 fits into a lip flange 2^a projected from the frame B on the side opposite the projected flange 2 and of the same shape as the lip flange 1^a on the sash bar, thus making a weather-tight joint. Above the middle sash bar 3, the contact strips 4 and 5 are attached to the ventilator by screws passed through the filler blocks 6 and 6^a, corresponding with the shape of the roll. Guides C are attached to outside lip flanges 2^a of the upper side frame bar, by rivets passed through the sides of the guides and similar guides C' are attached to the inside lip flanges 2^a of the lower side frame bar in a like manner. These guides, C and C', hold the screens D and E respectively. The guides C', however, are provided with metallic plugs 8 in their respective bottoms,

and through each plug is a central aperture through which passes the spring-pressed plunger 9, having a head 9^a, and a spring 9^b. These guides are rectangular shape in cross section with one side open and the outside face is slotted as at 10, so that the screen may be inserted by passing it through the slot 10 and raising it above the top of the guide until the lower end drops in the guide when it is then pulled down to its position of rest. The screens are provided with a screen frame 11 at the margins and the bottom of the screen frame 11 of the screen D, rests upon the periphery of the contact strip roll 5, while the top of the strip 11 of the lower screen E is pressed against the contact strip 4. The periphery of the contact strip 5 where the screen wipes it is the shape of a segment of a circle in cross section and the radii thereof are of such calculated length that the sash in revolving brings the contact strip always in contact with the stationary screen D. The upper screen is held 75 yieldingly against the contact strip 5 by gravity. The contact strip 4 is of a different shape (as shown in the drawings), its shape not being so material, providing its contour be such as to come within the range of the 80 spring controlled lower screen E. The inclined shape shown at 4^a does not depress the screen E as far as would be the case were the contact strip where it is wiped the shape of a segment of a circle. As the 85 sash revolves, the contact strip 5 slides accurately against the lower screen-frames of the upper screen D and the roll 4 depresses the screen E in its guides, and slides across its upper frame bar. This construction 90 eliminates the ungainly box screen, causes a saving in screen material and provides a screen which is insect proof and which is especially adapted for use in connection with ventilators used on the glazed portions of factories.

What I claim is:—

1. A screen for swinging sashes, having in combination with a frame and a sash revoluble therein, a contact strip attached to 100 said sash, and a screen yieldingly held by said frame and arranged to follow the periphery of the said contact strip, substantially as described.

2. A screen for swinging sashes, having in combination with a frame and a sash revoluble therein, a contact strip attached to said sash, a screen, a guide attached to said frame and arranged to hold said screen so that it slides on the periphery of said contact strip, and a spring-pressed plunger adapted to hold the said screen in yielding

contact with the contact strip, substantially as described

In testimony whereof, I sign this specification in the presence of two witnesses.

ROBERT B. SWART.
